Primary Examiner — T Chase Nelson*Assistant Examiner* — Christine Tucci(74) *Attorney, Agent, or Firm* — Greer, Burns & Crain, Ltd.(57) **CLAIM**

The ornamental design for a footwear outsole, as shown and described.

DESCRIPTION

FIG. 1 is a side perspective view of a footwear outsole showing our new design;

FIG. 2 is a rear perspective view thereof;

FIG. 3 is a side elevational view thereof;

FIG. 4 is a bottom view thereof; and,

FIG. 5 is a rear view thereof.

The broken lines in FIGS. 1-5 represent portions of the footwear that form no part of the claimed design. The broken line which defines the bounds of the claimed design forms no part thereof.

1 Claim, 5 Drawing Sheets(56)
